UNITED STATES PATENT OFFICE.

EMMETT N. CAMPBELL, OF MOLINE, ILLINOIS.

STUCCO-TOOL.

1,297,541.

Specification of Letters Patent. Patented Mar. 18, 1919.

Application filed March 26, 1918. Serial No. 224,826.

To all whom it may concern:

Be it known that I, EMMETT N. CAMPBELL, a citizen of the United States, residing at Moline, in the county of Rock Island and 5 State of Illinois, have invented certain new and useful Improvements in Stucco-Tools, of which the following is a specification.

This invention is a stucco tool and has for its principal object the production of a 10 device which will facilitate the completion of an accurate piece of work without the danger of injury to the hands of the user.

Another object of this invention is the 15 production of a stucco tool wherein the blade has a protector wall bent to extend at an acute angle thereto, thus allowing the handle which is connected to the wall to extend at such angle as will allow the blade to be held to apply the stucco to the sup- 20 porting surface without the danger of injury to the hands of the user.

Another object of this invention is the 25 production of a stucco tool wherein the handle is removably mounted upon the protector wall, the handle being supported so as to be firmly held against accidental movement although facilitating its removal when desired.

Broadly stated, this invention consists of 30 a blade having a protector wall extending at an acute angle thereto, a squared shank extending through the protector wall and having an internally threaded socket, a handle fitting upon said shank, a bolt projecting through the handle and engaging the shank for releasably holding the handle in a set position, on the protector wall.

With these and other objects in view, this 40 invention consists of certain novel combinations, constructions and arrangements of parts as will be hereinafter fully described and claimed.

One practical form of construction and 45 assembly of the present invention will be illustrated and described in the accompanying drawings, in which—

Figure 1 is a top plan view of the stucco tool, constructed in accordance with the present invention.

Fig. 2 is a central longitudinal section 50 through the tool, and

Fig. 3 is a section taken on the line 3—3 of Fig. 2, looking in the direction of the arrows.

Referring to the accompanying drawings 55 by numerals, it will be seen that the stucco

tool comprises a blade 5 having a protector wall 6, formed on one end thereof. It will be noted, upon referring to Fig. 1, that the blade 5 is preferably elongated and is rectangular, to perform the ordinary functions of a tool of this nature.

The wall 6 is bent to extend at an acute angle to the blade 5, as will be seen by referring to Fig. 2. This protector wall 6 extends entirely across the breadth of the blade 5 at the rear end thereof for purposes to be hereinafter set forth.

The shank 7 is provided with a head 8 on one end, although an internally threaded 70 socket 9 extends into the shank 7 from the opposite end thereof, as shown in Fig. 2. This shank is extended through an opening 10 of the same shape as the shank, this opening being formed through the protector wall 75 6. The washer 11 is positioned upon the shank to bear against the head of the shank and also against the wall 6, thus reinforcing the wall at the point through which the shank extends. The handle 12 is provided 80 with a socket 13 extending thereinto from its inner end and it will be noted that this socket 13 is square in cross section, as illustrated in Fig. 3. The bore 14 extends through the handle 12 from the outer end 85 thereof and communicates at its inner end with the socket 13. It is of course obvious that any suitable ornamentation may be provided for the handle without departing from the spirit of the present invention as 90 the device relates particularly to the retaining mechanism for holding the blade in engagement with the protector wall. The retaining bolt 15 is headed as indicated at 16, this head having a screw driver notch 16', 95 while at its opposite end it is externally threaded as shown at 17. Accordingly, this bolt 16 may be passed through the bore and the handle 12 to have its externally threaded end 17 screwed into engagement with the 100 shank by engaging the internally threaded socket 9 at this point. Therefore, it is obvious the bolt will hold the handle 12 in engagement with the shank 7 and accordingly, the engagement of the shank and handle 105 will cause this handle to be held against rotation.

In the use of the ordinary wooden paddle for stucco work, the paddle wears and for this reason does not produce a uniform 110 piece of work, while owing to the straight construction of the paddle, the hand of the

plasterer or user is often injured, while the strain necessary to hold the paddle firmly quickly tires the user.

In the present device, however, the flat blade may be employed to clean the surface to be stuccoed, while the angle at which the guard wall 6 extends from the blade 5 allows the handle to be easily gripped and the tool held to properly engage the surface being stuccoed, without imparting the strain or making it necessary to so firmly hold such a device as to cause such a strain, thus allowing the plasterer or user to hold the device longer before tiring. Furthermore, the production of the guard wall causes the user's hands to be protected, as the acute angle at which this wall extends causes the user's hand to be far enough from the work to prevent injury thereto. Furthermore, the detachable handle may be quickly applied to the shank and held thereon by the bolt, thus causing the entire device to be in position for proper operation. As above specified, the shank is squared to extend into a like-formed socket in the handle, passing through a squared opening in the wall, it is obvious the handle will be held against rotation upon this wall.

From the foregoing description, it will be seen that a very simple and efficient stucco tool has been provided wherein the device may be easily assembled and held in correct position for operation. Under such conditions, the same may be properly operated for performing such kinds of work, without causing the hand of the user to be injured, owing to the arrangement of the blade with respect to the wall and the manner in which the handle extends from this wall.

The foregoing description and the drawings have reference to what may be consid-

ered the preferred, or approved, form of my invention. It is to be understood that I may make such changes in construction and arrangement and combination of parts, materials, dimensions, et cetera, as may prove expedient and fall within the scope of the appended claim.

Having thus fully described my invention, what I claim as new and desire to secure by Letters Patent, is:—

In a device of the class described, the combination of a comparatively broad blade having a wall at one end, said wall having a squared opening formed therethrough at its central portion and in alinement with the central portion of said blade, a shank consisting of a squared body having a head on one end, said squared shank extending through the opening of said wall, thus keying said wall upon said shank, said shank having a threaded socket extending therein to form its inner end, a handle having a squared socket extending therethrough from one end, said handle also having a bore extending therethrough from the remaining end and communicating with the inner end of said last mentioned socket, and a headed retaining bolt extending through said bore and being screwed into the socket of said shank, thus holding said handle upon said shank, whereby pressure may be applied to said handle thence to the said blade through the medium of said shank, without twisting of the blade as pressure is applied adjacent either side edge of said blade.

In testimony whereof I affix my signature in presence of two witnesses.

EMMETT N. CAMPBELL.
